UNITED STATES PATENT OFFICE

CHARLES H. A. F. L. ROSS, OF BALNAGOWAN CASTLE, ROSS COUNTY,
SCOTLAND.

MAGAZINE BOLT-GUN.

SPECIFICATION forming part of Letters Patent No. 643,984, dated February 20, 1900.

Application filed December 29, 1897. Serial No. 664,364. (No model.)

To all whom it may concern:

Be it known that I, CHARLES H. A. F. L. Ross, baronet, a subject of the Queen of Great Britain, and a resident of Balnagowan Castle, 5 county of Ross, Scotland, have invented certain new and useful Improvements in Firearms, of which the following is a specification.

The invention is intended to be used particularly with magazine-guns and in general 10 form is a straight-pull breech-action.

The parts of the breech-action are, first, a receiver, in the forward end of which the gun-barrel is attached and along which the breech mechanism is slid backward and forward in 15 opening and closing the breech to throw out the cartridge-shells and reload, and, second, the breech mechanism, which is made up of a breech-bolt and extractor and a sleeve for rotating and thereby locking and unlocking 20 the breech-bolt and sliding it and the extractor along the receiver. On the sleeve is also a cover-plate or dust-guard for closing the receiver when the breech mechanism is pushed home.

25 The invention consists in the general combination of these parts.

In the accompanying two sheets of drawings, which form a part of this specification, Figure 1 is a plan view of that part of the gun 30 containing the breech-action and showing the breech closed, the receiver being in section along the line $x-x$ of Fig. 2 and the breech mechanism being partly broken away. Fig. 2 is a perspective view of the same with the breech closed, the parts being partly broken away. Fig. 3 is a perspective view of the 35 same with the breech open, the receiver and stock being in section on the line $y-y$ of Fig. 1 and the other parts being partly broken away. Fig. 4 is a section on the line $y-y$ of Fig. 1, showing the position of the parts when the gun is fired. Fig. 5 is a section across the gun on the line $z-z$ of Fig. 1. Fig. 6 is a perspective view of the receiver, partly broken 40 away. Fig. 7 is a perspective view of the breech-bolt with the firing-pin contained therein. Fig. 8 is a perspective view of the cover-plate or dust-guard. Fig. 9 is a perspective view of the sleeve and breech-bolt, and 45 Fig. 10 is a perspective view of the extractor. 50

In its general form the receiver A is a hol-

low cylinder and has a threaded portion 1, into which the rear end of the gun-barrel is screwed. Along the top the receiver is cut away behind the threaded end to form an 55 opening through which there is access into its interior. There is a longitudinal opening 2 through the under side of the receiver just back of the barrel, through which the cartridges pass from the magazine. At the rear 60 end there is another opening 3, through which the hammer passes. The receiver is provided with a suitable tail 4 for fastening it to the gun-stock. There is a narrow slot 14 in one side, through which a spring-actuated ejector 65 P projects to throw the exploded shell out of the receiver when the breech mechanism has been drawn back. The receiver is provided on its inner surfaces with suitable guides extending from its rear end forward nearly to 70 its front end to guide the breech mechanism as it is slid backward and forward. These guides consist of grooves 6, one on each side of the receiver, a guide-face 7 for the sleeve on one side, and a guide-face for the sleeve 75 and extractor on the other side, the last-named guide-face being formed by an extension of the under side of the groove 6. Immediately back of the threaded end of the receiver and adjoining the rear end of the barrel is a cylindrical chamber limited at its rear 80 by locking-shoulders 8, 9, which lie in a plane accurately at right angles to the axis of the gun. It is intended that the bolt-head of the breech-bolt shall revolve within this chamber 85 and shall be locked by the shoulders.

The breech-bolt consists of a bolt-head B and a stem 10, which is a hollow cylinder through which the firing-pin passes. On the bolt-head are two lugs 11, 12, which extend 90 outwardly on opposite sides. The height of these lugs is such that they will just clear in the chamber at the forward end of the receiver, and their rear ends are accurately faced, so as to bear evenly against the shoulders at the rear of the chamber to lock the bolt-head and prevent it from being driven 95 back by the explosion of the cartridge. The bolt-head is recessed in front, so as to provide a rim 13 to center the cartridge. There 100 is a groove 14 in the bolt-head at the proper place, as indicated, to permit the ejector P

to strike the cartridge. Back of the bolt-head and on the stem 10 are spiral ribs 15, forming parts of screw-threads. Their purpose is to rotate the bolt-head as the sleeve is pushed forward after the lugs on the bolt-head have cleared the locking-shoulders in the receiver. The bolt-actuator consists of a cover-plate or dust-guard C and a sleeve D. The cover-plate has on its under side a dovetail groove 16, formed by two inwardly-projecting ribs, by which it is rigidly attached to the sleeve, so as to leave a space between it and the breech-bolt within which the blade of the extractor lies. This cover-plate has a tongue 17, which slides in the groove 6 of the receiver. On the top of the sleeve is a dovetail rib 18, which engages the dovetail groove of the cover-plate. The rib 18 and a portion of one side of the groove are cut away to receive the tailpiece 22 of the extractor. There is also a tongue 19 on the side of the sleeve, which slides in the groove 5 of the receiver and, in conjunction with the tongue 17 on the cover-plate, guides the bolt-actuator. This tongue 19 is cut away except at its ends, and in the notch thus formed a latch L, positioned in the side of the receiver, engages and limits the range of movement of the sleeve in both directions. In the forward end of the sleeve 30 and on the inner wall thereof are cut spiral grooves 20, into which the spiral ribs 15 on the stem of the bolt-head slide. The spiral ribs should be of such a length that when the bolt-head is sufficiently rotated to unlock it 35 the ribs shall still engage with the spiral grooves in the sleeve. It is not material whether the sleeve or the bolt is grooved. Either may carry the spiral ribs and the other the spiral grooves. It is, however, preferable 40 to place the ribs upon the bolt-stem close to the bolt-head and the grooves in the forward part of the sleeve, as shown, as thereby the point of application of the power to rotate the bolt-head is brought into close proximity to 45 the locking-lugs thereon, avoiding the yielding that might result were the power transmitted through a long stem. By having the forward end of the grooves extending to and opening on the front end of the sleeve, as is 50 shown, this arrangement of the parts is permitted with the use of a bolt-stem of reduced diameter and an enlarged bolt-head, for were the grooves formed in the forward end of the bolt-head stem the stem would necessarily be 55 inserted in the sleeve from the rear thereof or the grooves be continued throughout the length of the stem, necessarily weakening it. The extractor E consists of a steel blade with a hooked end 21 to engage the rim on 60 the end of the cartridge and a projecting piece 22 to engage with the stops 23 24, formed by cutting away the dovetail joint between the cover-plate and the sleeve. These stops are so placed as to admit of a longitudinal movement of the extractor relatively to the sleeve which is equal to the longitudinal movement 65 of the sleeve relatively to the breech-bolt

while the latter is being rotated. It is important that the extractor shall not change its position longitudinally with respect to the bolt-head nor move on the head of the cartridge—that is to say, it should not rotate with the bolt-head. It is, moreover, advantageous to have the extractor free to be disengaged from the other parts of the breech mechanism when the latter is removed from the receiver, so that the parts can be readily separated and cleaned.

The firing-pin F, which passes through the center of the breech-bolt, is normally held rearwardly therein by the spring f with the rear shoulder of the firing-pin against the nut f', closing the rear of the bolt-stem; but when the gun is fired it is driven forward and strikes and explodes the cartridge which lies in the end of the gun-barrel G. The rear end of the firing-pin is struck by the hammer H, which is pivoted in the stock K. A thumb-piece is shown on the hammer for operating it by hand, and of course the hammer can be arranged to be set at half-cock, if desired. In order to prevent the hammer from striking the firing-pin, and thereby exploding the cartridge, unless the bolt-head is locked, there is the following arrangement: The hammer is engaged by the lower edge of the rim of the sleeve and is cocked by the latter when it is drawn back, and the firing-pin projects backward but a slight distance beyond the end of the sleeve when the latter is pushed home and is completely covered by the end thereof when the sleeve is drawn backward or is in any position except that of extreme forward, the firing-pin being contained in and moving with the breech-bolt, as already explained, and therefore not traveling backward while the bolt-head is being rotated. Thus unless the breech-bolt is pushed home far enough for the bolt-head to be at least partly engaged with its retaining-shoulders the firing-pin is covered completely by the rear end of the sleeve, and the head of the hammer is so shaped that it cannot strike the firing-pin unless the firing-pin extends substantially to the maximum distance back from the end of the sleeve. Therefore if the trigger should be pulled without the sleeve being first pushed home either the cartridge would not be exploded or the breech-bolt would be pushed home before the explosion could take place.

To assemble the parts of the breech mechanism, the sleeve is slipped onto the breech-bolt in such position that its spiral grooves fall over the spiral ribs in the breech-bolt, and the bolt-head is then pushed forward sufficiently to permit the extractor to be slid under the cover-plate with its hooked end in position over the front edge of the bolt-head. These parts, it will be seen, are all held together without a screw; but it may be desirable to secure the cover-plate in position by locking it to the sleeve by a screw. To insert the breech mechanism into the receiver, the

bolt-head and extractor are drawn forward until the bolt-head is rotated through the full distance through which it is intended to rotate and is held in that position, the ribs on the sleeve and cover-plate are brought into alignment with the guiding-grooves in the receiver, the latch L in the side of the receiver is pressed down, and the breech mechanism is pushed forward.

- 10 5. The operation of the parts is as follows: As the breech mechanism is pushed forward, the bolt-head is prevented from rotating because the side face of one of the lugs 11 bears against the guide-face 7 on one side of the receiver and the other side face of the same lug bears against the head of the extractor, which lies between it and the guide-face on the lower side of the groove 6, the latter thus forming an abutment for the extractor. So long as 15 20 the bolt-head cannot be rotated it must travel forward or back with the sleeve, owing to the engagement of the spiral ribs and grooves; but when the bolt-head has traveled far enough forward for the lugs to clear the locking-shoulders in the receiver the bolt-head and the extractor are stopped from forward motion by the end of the gun-barrel, and as the sleeve is pushed farther forward the bolt-head rotates and is locked in the receiver.
- 25 30 35 When the breech mechanism is fully withdrawn, a cartridge is forced up from the magazine M by a suitable spring into position to be driven forward into the barrel, the rim of the cartridge passing between the hooked end of the extractor and the bolt-head. Owing to the presence of the ejector it will not rise fully into alignment with the barrel until the bolt-head has traveled forward slightly. The front end of the cartridge is guided into the barrel by a spring-stud N, which the bolt-head pushes out of the way on reaching the forward end of its movement. After the explosion the breech mechanism is drawn back. During the initial movement of the sleeve the bolt-head is held from movement longitudinally. When it has been rotated far enough to free its lugs from the shoulders in the receiver and further rotation is prevented by a lug striking the extractor, it enters the guides of the receiver and follows the sleeve backward. When the breech mechanism has been drawn nearly the full distance, the ejector P strikes the rim of the cartridge and kicks it out at the top of the receiver, and the latch L on the side of the receiver engages with a shoulder on the rib on the sleeve, and the breech mechanism is prevented from being farther withdrawn.
- 40 45 50 55 60 65 70 75 80 85 90 95 100 105 110 115 120 125 130

The invention herein described is applicable to a machine-gun of the general style described in my other application, Serial No. 634,558, filed April 30, 1897, for an automatic firearm.

It will be seen that the function of the bolt-head is to push the cartridge forward into the barrel and hold it there against the recoil of the explosion. The function of the extractor

is to draw the cartridge-shell back with the bolt-head and prevent the latter from rotating farther than is necessary to free it from the locking-shoulders. The function of the rest of the breech mechanism is to cover the slot in the receiver, so as to protect the interior from the weather, and also to effect the rotation of the bolt-head and in the construction shown to draw the bolt-head backward and forward.

What I claim, and desire to secure by Letters Patent of the United States, is—

1. The combination, with a receiver, of a breech-bolt, means for rotating the breech-bolt to unlock it from the receiver, and an extractor contacting with the breech-bolt to prevent undue unlocking rotation of the breech-bolt, substantially as described.

2. The combination with a receiver, of a breech-bolt provided with a bolt-head having locking-lugs thereon, a sleeve encircling the breech-bolt, means for moving the sleeve longitudinally relative to the breech-bolt, and means located near the front of the breech-bolt and immediately behind the bolt-head thereon for rotating the breech-bolt relative to the sleeve upon the longitudinal motion of the sleeve, substantially as described.

3. In a breech mechanism for firearms, the combination with a receiver, of a sleeve and a breech-bolt located within the sleeve and having spiral ribs formed thereon behind and adjacent to the forward end thereof the sleeve having spiral grooves, the forward ends of which open upon the forward end of the sleeve, the ribs and grooves co-operating to rotate the breech-bolt upon a longitudinal motion of the sleeve, substantially as described.

4. The combination with a receiver, of a sleeve, an extractor, a breech-bolt, means for rotating the breech-bolt relatively to both the sleeve and extractor, the extractor acting as a positive stop to limit rotation of the breech-bolt, and means for moving the sleeve longitudinally relative to the breech-bolt and extractor, substantially as described.

5. In a straight-pull breech mechanism for firearms, the combination with a receiver, a sleeve, an extractor, a breech-bolt, means to unlock the breech-bolt from the receiver by rotating it relatively to the sleeve and to the extractor and against the extractor as a stop, and a fixed abutment for the extractor adapted to prevent the displacement thereof when struck by the breech-bolt, substantially as described.

6. In a breech mechanism for firearms, the combination with a receiver having guides for a sleeve therein, a sleeve sliding in the receiver, a breech-bolt, means for imparting a rotary locking or unlocking motion to the breech-bolt by the longitudinal motion of the sleeve, and an extractor, limiting the unlocking motion of the breech-bolt by having its one edge in engagement therewith and its opposite edge in engagement with guides upon the receiver, substantially as described.

7. In a breech mechanism for firearms, the combination with a centrally-recessed receiver having a shoulder thereon and having a longitudinal slot in one side, of a rigidly-connected sleeve and cover-plate, the sleeve sliding within the central recess of the receiver and the cover-plate in the longitudinal slot thereof, and closing it when the breech-bolt closes the breech, a breech-bolt having locking-lugs upon its forward end, means for rotating the breech-bolt by the longitudinal motion of the sleeve and cover-plate, and an extractor limiting the unlocking rotation of the breech-bolt, contained between the cover-plate and sleeve and having a limited longitudinal motion in relation thereto, the extractor bearing upon the shoulder formed upon the receiver to prevent its displacement by the rotating breech-bolt, substantially as described.
8. In a breech mechanism for firearms the combination with a breech-bolt, of a firing-pin, a hammer and a movable safety-stop preventing the contact of the hammer with the firing-pin while the breech-bolt is unlocked and moved by the hammer to lock the breech-bolt and to uncover the firing-pin for contact with the hammer, substantially as described.
9. The combination, in a straight-pull breech-closing mechanism, of a sleeve, a breech-bolt longitudinally movable and revolvable in respect to the sleeve and rotated by the longitudinal motion thereof for locking the breech, and a firing-pin, the rear end of the sleeve protecting the firing-pin from contact with the hammer until the sleeve is forced fully home, and whereby the sleeve may be forced home by the hammer to lock the breech-bolt, substantially as described.
10. In a breech mechanism for firearms, the combination with a sleeve, of an extractor, longitudinally movable in respect thereto, a breech-bolt longitudinally movable and revolvable in respect to the sleeve and revolvable in respect to the extractor, and coacting abutting faces on the extractor and sleeve whereby the sleeve imparts a longitudinal motion to the extractor, substantially as described.
11. In a breech mechanism for firearms, the combination, with a sleeve, an extractor longitudinally movable in respect thereto, a breech-bolt longitudinally movable and revolvable in respect to both the sleeve and extractor and coacting abutting faces on the extractor and sleeve whereby the sleeve imparts a longitudinal motion to the extractor, substantially as described.
12. In a breech mechanism for firearms, the combination, with a sleeve having a slot therein, a longitudinally-sliding extractor having a projecting piece contained in the slot and engaging the sleeve by which it is moved, a breech-bolt, and means for rotating the bolt and moving it longitudinally by the longitudinal movement of the sleeve, substantially as described.
13. In a breech mechanism for firearms the combination, with a longitudinally-moving and rigidly-connected sleeve and cover therefor, of a breech-bolt, means for causing a rotary motion of the breech-bolt by the longitudinal motion of the sleeve, and an extractor having its stem slidingly held between the sleeve and cover and a projection on the sleeve, to engage and move the extractor, substantially as described.

Signed by me in New York city this 10th day of December 1897.
